CLAIM

The ornamental design for a vehicle light bar, as shown and described.

DESCRIPTION

FIG. 1 is a perspective view of a vehicle light bar that embodies our ornamental design

FIG. 2 is a left side view thereof, the right side view being a mirror image of the left side view.

FIG. 3 is a top view thereof.

FIG. 4 is a bottom view thereof.

FIG. 5 is a front view thereof.

FIG. 6 is a back view thereof; and,

FIG. 7 is a perspective view of the vehicle light bar shown attached to a vehicle.

The In the drawings, the broken lines depict environmental subject matter that forms no part of the claimed design.
